ELECTRIC HEARING APPARATUS FOR THE
DEAF

Héctor Pescador, Mexico, D. F., Mexico

Application May 4, 1938, Serial No. 206,051

1 Claim. (Cl. 179—107)

This invention relates to electric hearing apparatus for the deaf.

Deafness is often caused by calcination of the joints of the auditory ossicles of the ear so that the ossicles have lost their normal capability of vibrating. Conventional electric hearing devices either vibrate the auditory ossicles by an ear phone acting on the air in the air passage of the ear, or by a pin connected to the diaphragm of the ear phone. Such apparatus to a limited extent are successful, according to the degree of calcination of the joints of the ossicles but all fail in severe cases of calcination such as deaf mutes.

15 I have discovered that when sound vibration, and an electric current modulated by the sound vibration, are simultaneously applied to the tympanum and auditory ossicles of the ear, the aggregate effect of both agencies restores approximately normal capability of vibrating to the auditory ossicles, and with the attaining of this, speech and musical sounds are heard even by a deaf mute.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming part of this specification,

Figure 1 is a side elevation of an ear phone for simultaneously applying sound vibrations and an electric current modulated by the sound vibrations to the ear.

Figure 2 is a rear elevation of the ear phone shown in Figure 1.

40 Figure 3 is a longitudinal section of the ear phone and showing the diaphragm vibrated pin and a screw carried by the pin for attaching an electric current supply wire.

Figure 4 is a diagrammatic view showing the electrical connections of the apparatus.

Referring now to the drawing in which like characters of reference designate similar parts in the various views, 10 designates the casing of an ear phone, the same having ventilating openings 11 in the circular wall and ventilating openings 12 in the rear wall to ventilate the ear 13. A diaphragm 14 is confined against the circular wall by a screw cap 15 and is vibrated in the usual manner by electro-magnet coils 16

which conduct audio frequency current in the usual manner to the magnet coils.

In carrying out the invention a metal rod 17 is screw threadedly engaged as shown at 18 with a nut 19 which is formed integral with the diaphragm to permit the rod to be adjusted axially with relation to the diaphragm. The rod is provided at its inner end with a spherical head 20 adapted to contact with the auditory members of the ear such as the tympanum and ossicles 10 or bony parts of the ear contiguous to the tympanum. The rod projects rearwardly through an opening 21 in the rear wall 22 of the ear phone and is terminally equipped with a binding post 23 through the medium of which an electric current supply wire may be attached to the rod. A tube 24 of insulating material is sleeved on the rod between the nut 19 and the head 20 and insulates the rod from the fleshy structure of the ear.

In the present embodiment of the invention illustrated in Figure 4, a transformer is employed having a primary winding 25 and two secondary windings 26 and 27, both secondary windings having the same number of turns. The primary winding is connected in series with a microphone 28 and a battery 29. The terminals of the ends of the secondary winding 26 which receive the electric pulsations into which the sound from the microphone has been transformed, are connected by circuit wires 30 and 31 to the magnet coils 16 of the ear phone, which latter function in the usual way to vibrate the diaphragm 14 and rod 17. A variable resistance 32 is connected across the circuit wires and functions as a volume control for the ear phone.

The electric current which is to be applied to the interior of the ear is taken from the secondary winding 27. This current will correspond in variations to the intensity of sound but should be less intense to accommodate the sensitivity of the interior of the ear. Accordingly connected across the circuit wires 33 and 34 which lead from the ends of the secondary winding 27 are disclosed two capacities 35 (00001). In the upper circuit wire 33 are two capacities 36 and 37 the latter being variable through three different capacities as shown. An independent source of electricity such as a battery 38 is connected in parallel with the circuit wires 33 and 34 and a rheostat 39 is connected across the wires 33 and 34 to control the intensity of the current supplied to the ear through the wire 33 which is connected by means of the binding post 23 to the 55

rod 17. The circuit wire 34 is grounded to the body of the user beyond the rheostat 39.

In operation at the same time the sound vibrations are imparted to the tympanum and auditory ossicles of the ear through the medium of the rod 17 and head 20, direct electric current will be supplied from the battery 38 to the tympanum and auditory ossicles, modulated by the pulsations set up in the secondary winding 27 of the transformer. The various capacities 35, 36 and 37 and rheostat 39 permit of regulating the modulated current to accommodate the sensitivity of the interior of the ear.

From the above description it is thought that the construction and operation of the invention will be fully understood without further explanation.

What is claimed is:

An electric hearing apparatus for the deaf, comprising an ear phone magnet, a diaphragm vi-

brated by the magnet, a metal rod extending through the center of the diaphragm, means for connecting the rod to the diaphragm to permit the rod to be adjusted axially with relation to the diaphragm, a spherical head on the inner end of the rod adapted to contact with the auditory members of the human ear, a transformer of audio frequency current having two secondaries, a circuit electrically connecting one of the secondaries and the magnet, a circuit electrically connecting the other secondary to the rod, capacities in the last named circuit, and a separate source of electricity connected in the last named circuit, the arrangement being such that sound vibrations and an electric current modulated by the sound vibrations may be simultaneously applied through the metal rod and spherical head to the auditory members of the human ear.
